METHOD OF MANUFACTURING RADIALLY CORRUGATED DISKS

John A. Spencer, Newtonville, Mass., assignor, by mesne assignments, to General Plate Company, Attleboro, Mass., a corporation of Massachusetts

Original application June 26, 1930, Serial No. 463,961. Patent No. 1,895,590, dated January 31, 1933. Divided and this application January 26, 1933, Serial No. 653,701.

3 Claims. (Cl. 153—2)

This invention relates to methods of manufacturing radially corrugated disks, and with regard to certain more specific features, to methods adapted to commence with uncorrugated blanks.

5 This application is a division of my Patent No. 1,895,590, granted January 31, 1933, upon an application, Serial No. 463,961, filed June 26, 1930, for Snap-acting devices.

10 Among the several objects of the invention may be noted the provision of a method of manufacturing radially corrugated disks which commences with uncorrugated blanks of either resilient ordinary metal or "composite thermostatic metal" (such as bimetal), and produces snap-acting disks which are thermostatically sensitive, if composite metal has been used; a method of the class described which achieves the desired 15 ultimate conformation without in the process subjecting the blanks to any undue localized stresses which might impair the efficiency of the resulting article; and the provision of a method of the class described which is simple and economical in operation, requiring but a minimum of specialized machinery. Other objects will be 20 25 in part obvious and in part pointed out herein-after.

The invention accordingly comprises the elements and combinations of elements, and steps and sequence of steps, which will be exemplified 30 in the method hereinafter described, and the scope of the application of which will be indicated in the following claims.

In the accompanying drawings, in which are illustrated one or more of various possible embodiments of the invention,

Fig. 1 is a plan view of one form of blank utilized in the present method;

Fig. 2 is a plan view of an alternative form of blank;

40 Fig. 3 is a perspective view illustrating a first operation on a Fig. 1 type blank;

Fig. 4 is a front elevation of a roller used in the step illustrated by Fig. 3;

Fig. 5 is a back elevation of the roller shown 45 in Fig. 4;

Fig. 6 is an elevation illustrating a first operation on a Fig. 2 type of blank;

Fig. 7 is a side elevation of the roller arrangement used in the step illustrated in Fig. 6;

50 Figs. 8, 9, and 10 illustrate successive steps applied to either of the types of blanks shown, after the first operation has been performed thereon; and,

Fig. 11 is a top plan view of a finished, radially corrugated disk.

Similar reference characters indicate corresponding parts throughout the several views of the drawings.

As disclosed in my Patent No. 1,895,590, of which this application is a division, radially corrugated disks having a slight initial conical conformation, when made of suitable material, are useful as snap-acting elements. If the material is resilient sheet metal, the disk constitutes a valuable over-centering element; while if the 10 material is composite thermostatic metal (such as bimetal) formed of a plurality of united metallic layers having different coefficients of thermal expansion, the disk is a valuable self-actuating, snap-acting thermostatic unit. The present 15 application is not concerned with the actions and reactions of these disks per se, which are adequately discussed in said patent, but in a preferred method (or methods) of manufacturing the same. The method used, particularly if the 20 disks are thermostatic ones, needs to be such that no excessive localized stresses are produced in any one region of the disk, otherwise the temperature response characteristics of the disk might be seriously impaired. To a lesser extent, 25 the same requirement is imposed upon the manufacture of the non-thermostatic disks, as localized stresses in such disk mean early failure, in operation, of that portion of the disk unduly strained, and thus shorter life of the disks taken 30 on the average.

The method which I have found to be most advantageous comprises initially corrugating blanks with a roller system, and then pressing the corrugated blanks into final conformation in a series of die-press steps. In this manner, no great stress is introduced into any one part of the disk at any time, but rather, the stresses are more 35 equally distributed through the whole disk from step to step, and the finished article is thus free 40 of any excessive localized stresses.

Referring now more particularly to the drawings, Figs. 1 and 2 illustrate blanks typical of the types I use for the manufacture of the disks in question. Fig. 1, at numeral 1, shows a flat 45 annulus. Fig. 2, at numeral 2 shows a short cylindrical section, which may be cut from a (preferably seamless) tube or pipe. Economically speaking, the cylindrical blank 2 is more 50 advantageous than the annular blank 1, as there is less waste in cutting the blank from its stock. The metal stock from which these blanks are cut comprises either springy, resilient sheet metal such as thin steel or spring brass, in case the ultimate disk is to be non-thermostatic, or any 55

suitable form of composite thermostatic metal (such as that shown in Marshall Patent 1,481,021, Marshall Patent 1,700,173, or Bush Patent 1,870,235) in case the ultimate disk is to be thermostatic. So far as the present invention is concerned, it is inconsequential whether the blank is for a non-thermostatic or a thermostatic disk.

In their initial steps, the blanks 1 and 2 are subjected to somewhat different operations, the purpose of which is to corrugate the blank in the desired manner and, at the same time, shape it into either a cylindrical form or a conical form in which the apex angle of the cone is so small that it is nearly a cylinder.

15 The flat annular blank 1 is passed through a pair of corrugating rollers 3 (see Figs. 3). The rollers 3 resemble bevel gears in appearance, but the shape of their teeth is preferably not like that of the usual bevel gears. As shown in Figs. 20 4 and 5, the teeth 4 of the rollers 3 taper in width from front to back, being narrowest in the front (or smallest diameter) region, and broadest in the back (or greatest diameter) region. The teeth of the two rollers 3 of course 25 mesh, so that the one may drive the other. The shaping of the teeth 4, coupled with the "bevel" of the rollers 3, forms the flat blank into a cylindrical shape which tends to be slightly conical, as illustrated, at the same time that it is corrugated. In operation, the rollers are separated 30 (suitable means for this being provided) and the blank inserted therebetween, in such manner that the meshing teeth of the two rollers will occupy radial positions on the annulus blank. 35 After forcing the rollers together, they are rotated and the blank is guided to maintain the original relationship (teeth radial to the annulus), while the rollers corrugate and simultaneously shape the blank. The shape of the teeth 4 is previously calculated so that the corrugations on the blank come out without any 40 overlapping. After one or more rotations of the blank, the rollers are separated and the blank, now corrugated and cylindrical, or slightly conical, is removed.

The cylindrical, or tubular blank 2, being originally of cylindrical conformation, is corrugated in the manner shown in Figs. 6 and 7. In these figures, numeral 5 indicates a pair of toothed, 50 meshing rollers which resemble pinions in construction. The teeth 6 of the rollers 5 are parallel. In operation, the rollers 5 are separated, the blank 2 introduced therebetween in such manner that the elements of the cylinder constituting the blank are parallel to the teeth 6, the rollers 5 are again forced together and then rotated. As previously, the pitch and dimensions of the teeth 6 are established such that there is no overlapping of the resulting corrugations in the blank 2. After one or more rotations of the blank 2, the rollers are separated and the now completely corrugated, and cylindrical blank is removed.

Since the subsequent steps are substantially identical for either original type of blank, the numeral 1 is used in the remaining figures to indicate such blanks after their first operation has been finished. That is, numeral 1 indicates the blank (either of the Fig. 1 or the Fig. 2 type) after its initial working and after commencement of the next operation to be described.

The blank 1 is placed in a die 8 (Fig. 8), which has a circular depression or counterbore 9 therein. The depression 9 is relatively shallow, as it constitutes more a stop or movement limiting

means than an actual shaping means. A second die 10 is now brought down on the blank 1. The die 10 includes a frusto-conical depression 11 located centrally therein. The walls of the depression 11 are preferably slanting at only a relatively slightly greater angle than the sides of the blank 1. The die 10 automatically centralizes the blank 1 therein. The die 10 is now driven downwardly against the blank 1. The effect of this is to make the blank 1 more conical (the apex angle 10 becoming less acute) through a simultaneous stretching of the outer peripheral regions of the corrugations and compression of the inner peripheral regions of the corrugations. This continues until the slope of the blank sides is the same as 15 that of the walls of the depression 11. Usually by the time this equivalency of slope is obtained (and with the first die) the lower end of the blank, and hence the base of the cone, has expanded (see Fig. 9) until it reaches the sides of the circular depression 9 in die 8. The circular depression, from this time forth, positively bars further expansion at the periphery of the blank and thus forces all additional shaping to take place by compression of the corrugations at 20 the inner peripheral region. By this means are the disks held to a uniform size.

The die 10 is now removed and replaced by a die 12 having a similar conical depression 13, which depression has walls at a greater slope than 30 those of the die 10. The effect hereby produced is to further flatten the blank, this time entirely by compressing and further increasing the amplitude of the central portion of the corrugations. 35

Finally, the die 12 is removed and replaced by 40 a simple flat-surface die 14, which is pressed down upon the now relatively narrow apex of the conical blank to bring said blank to its final shape, which depends upon how great a throw of the snap-acting element is desired.

The die pressing illustrated in Figs. 8, 9, and 10 may be done in any number of steps suitable to the disk being formed and the shaping characteristics of the metal of the blank. The number shown (three: two conical-depression dies 10 45 and 12 and one flat die 14) has been found to give excellent results without introducing substantial localized stresses in the resultant disk.

Fig. 11 illustrates a completed disk, formed in accordance with the present invention. It will 50 be seen that its corrugations 15 are positioned in the desired radial conformation, and it will be apparent that it has the desired slightly conical conformation.

It will be seen that the present invention comprises taking a blank and corrugating it in such a manner that it comes out a corrugated cylinder or 55 nearly a cylinder, and thereafter so pressing the blank that the corrugations at one end of the cylinder are slowly compressed, while the corrugations at the other end of the cylinder are stretched or held in shape, until the blank as a whole assumes a disk-like appearance. At no 60 time during this sequence of events is there localized substantial stress introduced which might deleteriously affect the operation of the produce article.

In view of the above, it will be seen that the several objects of the invention are achieved and 70 other advantageous results attained.

As many changes could be made in carrying out the above constructions and processes without departing from the scope of the invention, it is intended that all matter contained in the above 75

description or shown in the accompanying drawings shall be interpreted as illustrative and not in a limiting sense.

I claim:

5 1. The method of manufacturing radially corrugated snap-acting disks comprising preparing a seamless blank in the form of a flat annulus, corrugating said blank with rollers in such manner that it assumes a substantially cylindrical conformation wherein the individual corrugations are of rounded contour, and compressing the corrugations at one end of the blank inwardly until the blank assumes a disk conformation in which the central portion is slightly displaced from the 10 peripheral portion.

15 2. The method of manufacturing radially corrugated snap-acting disks which comprises preparing an endless blank, corrugating said blank and imparting to the individual corrugations a rounded contour, compressing the corrugations at one edge of the blank, while at the same time 20

expanding the corrugations at the other edge of the blank, thereby imparting an approximately disk shape to the blank, and leaving the central portion of the disk shape slightly displaced from the peripheral portion.

3. The method of manufacturing radially corrugated snap-acting disks which comprises preparing an endless blank, corrugating said blank and imparting to the individual corrugations a rounded contour, compressing the corrugations 10 at one edge of the blank, while at the same time expanding the corrugations at the other edge of the blank, and thereafter continuing the compression of corrugations at the respective edge of the blank, while discontinuing the expansion of 15 the corrugations at the other edge of the blank, thereby imparting an approximately disk shape to the blank, and leaving the central portion of the disk shape slightly displaced from the peripheral portion.
